Atty.

UNITED STATES PATENT OFFICE.

MOSES F. CARR, OF LEXINGTON, MASSACHUSETTS, ASSIGNOR TO CARR FASTENER COMPANY, OF CAMBRIDGE, MASSACHUSETTS, A CORPORATION OF MAINE.

FASTENER.

Application filed January 22, 1924. Serial No. 687,748.

To all whom it may concern:

Be it known that I, MOSES F. CARR, a citizen of the United States, and a resident of Lexington, in the county of Middlesex,

5 State of Massachusetts, have invented an Improvement in Fasteners, of which the following description, in connection with the accompanying drawings, is a specification, like characters on the drawings representing like parts.

10 This invention pertains to improvements in fasteners.

15 It is among the objects of the invention to improve and simplify the construction of fasteners of the type wherein separation of stud and socket may only be effected by relative tipping movement between them at one side.

20 In the drawings, which show a preferred form of one embodiment of my invention:—

Figure 1 is a front elevation of a fastener, the socket secured to its carrying fabric;

Fig. 2 is a section on the line 2—2 of Fig. 1, being partly in elevation;

25 Fig. 3 is a section on the line 3—3 of Fig. 2, being partly in elevation;

Fig. 4 is a rear elevation of the socket prior to its assembly with the fabric and back plate; and

30 Fig. 5 is a longitudinal section of the back plate or clench plate.

Referring to the preferred embodiment of my invention illustrated in the drawings, I have shown a stud including a head 5, neck 6, and shank 7 secured to a stud-carrying part 8, which may be the body of a motor car. This stud may be of the character defined in my United States Letters Patent No. 1,365,023 issued January 11, 1922, and 35 co-acting in substantially like manner with the cooperating socket.

40 The socket illustrated includes a casing 9 containing a spring 10 presenting generally parallel jaw portions 11 and 12 adapted to engage the neck 6 of the stud behind the head thereof. The casing includes a face portion, a peripheral wall and ears, as hereinafter explained.

45 The jaws 11 and 12, adjacent the free ends thereof, present shoulder portions 13 and 14 closely to embrace the neck of the stud while assisting release of the stud from between the jaws when the socket is pulled outwardly at the bottom, the assistance arising

50 from the action of the inclined shoulder rear-

wardly of the neck 6 against the shoulder portions 13 and 14 spreading the jaws and hence assisting release of the head of the stud from between the jaws.

55 In the present embodiment of my invention, the spring is held in the casing by ears or inwardly projecting portions of the casing wall bent inwardly from the edge thereof.

60 The top inwardly projecting portion 15 is relatively extended in area, presenting a surface to guide and back-support the free ends of the jaws, while permitting free lateral movement thereof in the general plane of the spring. Similarly, the bottom inwardly projecting portion 16 overlies and 65 back-supports those ends of the jaws which are connected to the body of the spring. The holding in place of the spring by the top and bottom inwardly projecting portions 15 and 16 may be supplemented by lateral inwardly bent holding lugs 15', herein shown as four in number.

70 To prevent cramping of the spring by the inwardly bent portion 15, I provide projections herein shown as lugs 20, 21, struck inwardly from the face of the casing and supporting the portion 15, while the inwardly bent portion 16, may be similarly spaced against cramping the action of the spring, but I 75 prefer to provide a lug 22 struck forwardly from the inwardly bent portion 16 and abutting against the inner surface of the casing. The lug 22 is preferably, as illustrated, so located as to come between adjacent portions 80 of the spring jaws, and contribute to correct alignment thereof.

85 The casing and spring are secured to a flexible socket-carrying fabric (usually a curtain) by prongs 24, which are integral with the casing and are adapted to pierce the curtain and clench against a back plate or clench plate 25, thus securing the casing and back plate firmly together and to the curtain.

90 The inwardly projecting portions 15', 15 and 16 of the casing, overlying the spring, provide surfaces pressed against the exterior surface of the socket-carrying fabric 23, and at the same time opposing such entrance of the fabric within the casing as might interfere with the proper functioning of the 95 spring jaws.

100 The back plate 25 has a stud-receiving aperture 26, three sides of which fit rela- 105

tively closely to the shank of the stud when the socket and stud are engaged, the upper part of the aperture being elongated to provide a clearance to allow tipping of the 5 socket relative to the stud by a pull in the direction of the arrow, as shown in Fig. 2.

Relative tipping movement between stud and socket in the three other directions is opposed by the engagement of the jaw portions 10 13 and 14 with the shoulder behind the neck of the stud, which, after a limited movement between stud and socket, is reinforced by the engagement of the head of the stud with the walls of the aperture 27 in 15 the face of the casing 9, co-acting with the engagement of the shank 7 of the stud with the relatively closely fitting sides and bottom of the stud-receiving aperture in the back of clench plate 25.

20 In use the fastener is to a large extent subjected to strain on the socket in an outward direction above the stud. While this strain cannot separate the stud and socket, I have found it desirable to minimize the 25 wear arising from this strain by providing a relatively extended bearing surface or lip 28 on the back plate 25 at that side thereof opposite the extended side of the stud-receiving aperture. This relatively extended 30 bearing surface 28 is preferably, as illustrated, provided by a portion of the back plate projecting first rearwardly, in a direction away from the socket, and then projecting forwardly, terminating adjacent the 35 plane of the inner surfaces of the jaws 11 and 12. The bearing surface 28, as viewed in Fig. 3, is curved generally to conform to the shape of the stud-receiving aperture, and is preferably of greatest extent at the 40 bottom, narrowing toward the top thereof, as best shown in Fig. 5. Thus a lip is provided which may also serve to hold the edge of the fabric, around the stud-receiving aperture therethrough, away from the stud 45 and prevent fraying of the edge by the stud, with attendant possible interference with the proper functioning of the jaws 11 and 12.

50 While I have shown and described a preferred embodiment of my invention, it will be understood that I have done so for purposes of clarification, and not for purposes of limitation. The scope of my invention is best defined by the following claims.

55 Claims.

1. A socket for a three-side lock fastener presenting a casing adapted to be located on that side of the socket-carrying fabric opposite the side from which the stud enters the socket, a spring in said casing presenting two jaws having adjacent free ends, said casing formed from a single piece of metal presenting a face portion, a peripheral wall, and an inwardly projecting spring-retaining portion extended to provide a relatively

wide guiding and back-supporting surface for the free ends of said jaws, said socket also presenting a combined back plate and clench plate for location on the opposite side of the socket-carrying fabric from said casing, said clench plate having a stud-receiving opening therethrough having a wall relatively closely embracing the shank of the stud at three sides to oppose relative tipping movement between stud and socket in three directions, while extended in a direction toward the free ends of said jaws to provide a clearance at the fourth side to permit such relative tipping movement in that direction to disengage the stud and socket. 70 75 80

2. A socket for a three-side lock fastener presenting a casing adapted to be located on that side of the socket-carrying fabric opposite the side from which the stud enters the socket, a spring in said casing presenting two jaws having adjacent free ends, said casing formed from a single piece of metal presenting a face portion having an opening therein presenting a wall embracing the head of the stud, a peripheral wall, and an inwardly projecting spring-retaining portion extended to provide a relatively wide guiding and back-supporting surface for the free ends of said jaws, said socket also presenting a combined back plate and clench plate for location on the opposite side of the socket-carrying fabric from said casing, said clench plate having a stud-receiving opening therethrough having a wall relatively closely embracing the shank of the stud at three sides to oppose, while co-acting with the wall of said opening in said face portion, relative tipping movement between stud and socket in three directions, while extended in a direction toward the free ends of said jaws to provide a clearance at the fourth side to permit such relative tipping movement in that direction to disengage the stud and socket. 90 95 100 105 110

3. A socket for a three-side lock fastener presenting a casing, a spring in said casing presenting two jaws for engagement on opposite sides of a cooperating stud, said casing formed of a single piece of metal presenting a face portion, a peripheral wall and an inwardly projecting spring-retaining portion extended to provide a relatively wide guiding and back-supporting surface for said jaws above the stud-engaging portions thereof, said socket also presenting a back plate for location on the opposite side of the socket-carrying fabric from said casing, said back plate having a stud-receiving opening therethrough having a wall relatively closely embracing the shank of the stud at three sides to oppose relative tipping movement between stud and socket in three directions, while extended at the fourth side toward said back-supporting 115 120 125 130

surface to permit such relative tipping movement in a direction to disengage the stud and socket.

4. A socket for a three-side lock fastener 5 presenting a casing, a spring in said casing presenting two jaws for engagement on opposite sides of a cooperating stud, said casing formed of a single piece of metal presenting a face portion, a peripheral wall 10 and two inwardly projecting spring-retaining portions extended to provide relatively wide guiding and back-supporting surfaces for said jaws above and below the stud-engaging portions thereof, said socket also 15 presenting a back plate for location on the opposite side of the socket-carrying fabric from said casing, said back plate having a stud-receiving opening therethrough having a wall relatively closely embracing the 20 shank of the stud at three sides to oppose relative tipping movement between stud and socket in three directions, while extended at the fourth side, toward said back-supporting surface above the stud, to permit 25 such relative tipping movement in a direction to disengage the stud and socket.
5. A socket for a three-side lock fastener comprising a casing presenting at top and bottom inwardly projecting portions integral therewith, lugs supporting the free ends of said inwardly projecting portions, a spring in said casing presenting parallel resilient jaws guided and back-supported for free movement beneath said inwardly 30 projecting portions, and a back plate presenting a stud-receiving aperture, said casing and back plate adapted to be assembled with the socket-carrying fabric interposed between them and with the fabric tightly 35 pressed against said inwardly projecting portions while the latter are supported by said lugs to oppose bending of said inwardly projecting portions and resultant interference with the free movement of said jaws.
- 40 6. A socket for a three-side lock fastener comprising a casing, a spring in said casing and a back plate secured to said casing on the opposite side of the socket-carrying fabric from said casing, said back plate having a stud-receiving aperture therethrough and having a lip extending forwardly therefrom toward the plane of the spring in said casing, said lip presenting an extended wear-resisting bearing surface against the shank 45 of the stud when the latter is engaged with said socket.
7. A socket for a three-side lock fastener comprising a casing, a spring in said casing and a back plate secured to said casing on the opposite side of the socket-carrying fabric from said casing, said back plate having a stud-receiving aperture therethrough and having a lip extending first rearwardly from the general plane of said back plate 50 and then forwardly therefrom toward the 55 plane of the spring in said casing, said lip presenting an extended wear-resisting bearing surface against the shank of the stud when the latter is engaged with said socket.
8. A socket for a three-side lock fastener 60 comprising, in combination, a casing, a casing-securing part for application to the opposite side of the socket-carrying fabric from said casing, a spring in said casing, said casing formed of a single piece of metal 65 presenting a face at one side of said spring, a peripheral wall around said spring and an ear thrown inwardly from said peripheral wall to overlie said spring, said ear guiding and back-supporting movable jaw 70 portions of said spring, and a projection 75 spacing said ear from the inner surface of said face to oppose binding of said movable jaw portions by said ear.
9. A socket for a three-side lock fastener 80 comprising, in combination, a casing, a casing-securing part for application to the opposite side of the socket-carrying fabric from said casing, a spring in said casing, said casing formed of a single piece of metal 85 presenting a face at one side of said spring, a peripheral wall around said spring and an ear thrown inwardly from said peripheral wall to overlie said spring, said ear guiding and back-supporting movable jaw 90 portions of said spring, and a projection thrown backwardly from said face portion 95 spacing said ear from the inner surface of said face to oppose binding of said movable jaw portions by said ear.
10. A socket for a three-side lock fastener 100 comprising, in combination, a casing, a casing-securing part for application to the opposite side of the socket-carrying fabric from said casing, a spring in said casing, said casing formed of a single piece of metal 105 presenting a face at one side of said spring, a peripheral wall around said spring and an ear thrown inwardly from said peripheral wall to overlie said spring, said ear guiding and back-supporting movable jaw 110 portions of said spring, and projections located on the opposite sides of said movable jaw portions spacing said ear from the inner surface of said face to oppose binding of 115 said movable jaw portions by said ear.
11. A socket for a three-side lock fastener 120 comprising, in combination, a casing, a casing-securing part for application to the opposite side of the socket-carrying fabric from said casing, a spring in said casing, said casing formed of a single piece of metal 125 presenting a face at one side of said spring, a peripheral wall around said spring and an ear thrown inwardly from said peripheral wall to overlie said spring, said ear guiding and back-supporting movable jaw portions of said spring, and a projection thrown forwardly from said ear between said movable jaw portions and spacing said ear from 130

the inner surface of said face to oppose binding of said movable jaw portions by said ear.

12. A clench plate for separable fasteners presenting an elongated stud-receiving aperture and an extended bearing surface for a stud partly surrounding said stud-receiving aperture extending transversely forwardly and rearwardly from the general plane of 10 said clench plate.

13. A socket for three-side lock fasteners comprising a casing, a spring contained in said casing and a back plate secured to said casing with a carrying fabric interposed

and gripped between them, said casing presenting an opening for receiving the head of a stud, said opening intersected by resilient parallel jaw portions of said spring, said spring held in said casing by spring-retaining projections, two of which overlap 20 the opposite ends of said resilient jaw portions and are spaced away from said casing by integral supports to prevent cramping of said jaws when said casing is secured to said carrying fabric.

In testimony whereof, I have signed my name to this specification.

MOSES F. CARR.
